BEAM DRIVING MECHANISM FOR SLASHERS

Arthur E. Silcox, Biddeford, Maine, assignor to
 Saco-Lowell Shops, Boston, Mass., a corpora-
 tion of Maine

Application April 18, 1944, Serial No. 531,583

9 Claims. (Cl. 28—39)

1

As is well understood by those familiar with the sizing machines known as "slashers," the size and squeeze rolls in the size box revolve at a constant speed and, consequently, pull yarn forward from the creel at a constant rate. The delivery roll or drag roll at the opposite end of the machine is connected with the driving mechanism for the rolls associated with the size box so that it takes up the yarn at exactly the rate at which it is delivered by the size rolls. However, the loom beam on which the yarn is wound immediately after leaving the delivery roll must revolve at a constantly decreasing speed as the diameter of the yarn body on it increases. For this reason, while the size and delivery rolls are positively driven, the loom beam is driven through a friction mechanism so arranged that, as the pull exerted on the yarn by it tends to increase with an increase in the diameter of the beam, the friction mechanism yields or slips sufficiently to prevent the loom beam from revolving any faster than is necessary to take up the yarn fed to it by the delivery roll.

In such an arrangement there is very little slippage in the friction driving mechanism for a time immediately after the winding of the yarn on the loom beam starts, but as the yarn body gradually builds up, the speed of the beam arbor slows down, with a corresponding increase in the amount of slip in the friction mechanism.

The modern tendency to use beams with larger heads, and thus to build up yarn bodies on them of greater diameter, creates a condition in which the slippage becomes very high as the winding operation on the beam nears completion, with the result that the friction mechanism overheats and the friction plates are subjected to excessive wear.

The present invention deals with the problem presented by these conditions and it aims to devise a driving mechanism for the loom beam in which the temperatures and rate of wear created in it will be held within entirely reasonable limits.

The nature of the invention will be readily understood from the following description when read in connection with the accompanying drawings, and the novel features will be particularly pointed out in the appended claims.

In the drawings,

Fig. 1 is a front elevation of a loom beam and a friction driving mechanism therefor organized in accordance with this invention;

Fig. 2 is a left-hand end view of the construction shown in Fig. 1; and

2

Fig. 3 is a vertical, sectional view taken approximately on the line 3—3, Fig. 1.

Preliminary to a detailed description of the construction shown in the drawings, it may be pointed out that this invention proposes to solve the problem above described by providing two friction mechanisms for driving the loom beam, one through a considerably higher speed range than the other, and to devise means for automatically shifting the drive from one mechanism to the other at an intermediate point in the building of the yarn body on the beam. Thus the slip and the resultant amount of heat created and of wear produced on the friction surfaces, will be maintained within reasonable limits in both mechanisms.

Referring first to Fig. 1, the loom beam is indicated at 2, supported on an arbor 3, one end of which extends loosely into the driving shaft 4, while the other end is mounted in the usual manner in a hole in a shaft supported at the opposite side of the machine. The arbor carries an arm 5 arranged to engage a stud 6 secured in a face plate 7 which is fixed on the driving shaft 4, these connections serving to revolve the beam in unison with its driving shaft.

The usual mechanism for revolving this shaft comprises a gear 8, Figs. 1 and 2, meshing with another gear 10 fast on a shaft 12 and driven by a pinion 13 on the shaft 14, Fig. 2. This shaft 12 drives the delivery roll 9 and its driving pinion 13 is connected with the mechanism for driving the size rolls at the same surface speed as the delivery roll, for the reasons above described.

Keyed to the shaft 4 are the hub sections of two friction disks 15 and 16. The gear 8, however, revolves freely on these hub sections, and it carries in rotation with it two circular plates *a* and *b*, both lying close to the inner surfaces of the respective friction plates 15 and 16. Outside the latter plates are two additional disks 17 and 18 which also lie close to the outer surfaces of the respective friction plates 15 and 16 and are connected with the edges of the respective plates *a* and *b* to revolve with them. These outside disks have hub sections revolving freely on the shaft 4. The friction plates 15 and 16 are surfaced with clutch facing material, and means is provided for forcing all of these revolving elements together so as to press those positively driven firmly against the plates 15 and 16 which, as above mentioned, are keyed to the shaft 4.

Consequently, when this action has been produced the shaft will be picked up and revolved

through the frictional contact of those parts at opposite sides of the respective plates 15 and 16 with these plates themselves.

The mechanism for so forcing these plates and disks together comprises a friction lever 20, Figs. 1 and 3, fulcrumed at 21 on a bracket 22 rigid with the machine frame. A weighting mechanism is provided to force the upper end of this lever toward the right including a disk-like head 23, integral with a graduated arm 23' on which weights 25 and 26 are mounted for adjustment, the head having an arm 27, Fig. 2, projecting laterally therefrom and arranged to engage the left-hand side of the upper end portion of the friction lever 20. This head 23 is mounted on a pivot stud 24, Fig. 3, to swing freely thereon.

Thus the weights 25 and 26 operate through the connections just described to force the lever 20 against the friction ring 28, Fig. 1, which crowds the latter against the disk 18 and thereby brings the friction mechanism into action, causing it to revolve the shaft 4 and the beam 2.

The mechanism above described is like that heretofore used, except for some certain modifications in the part 23 and its mounting provided for the purposes of this invention, but it operates in the same manner as does the prior art mechanisms to revolve the beam 2, and it has the same limitations as do the prior art constructions.

According to this invention the shaft 4 is extended to the left, as shown in Fig. 1, and another friction mechanism like that above described is mounted on it but is driven at a much slower speed. This second friction drive comprises a gear 30, considerably larger than the gear 8, and driven by a much smaller gear 31 fast on the shaft 12 above referred to. The parts of this mechanism corresponding to those of the previously described friction mechanism are designated by the same, but primed, numerals, and these parts are associated with the shaft 4 in the same manner as are the parts of the first friction mechanism. Also, the lever 20, above mentioned, cooperates with a collar 28' like that shown at 28, to bring the second friction mechanism into action to drive the shaft 4 and the beam 2 when the lever is swung to the left, Fig. 1.

Mechanism is provided to shift the drive automatically from the right-hand friction mechanism, Fig. 1, to the corresponding left-hand mechanism when the yarn body on the beam has attained approximately a predetermined diameter. Preferably this result is accomplished through the action of the press roll. That is, the machine is equipped with the usual press roll mechanism which includes a bracket 32, Figs. 1 and 3, carrying a pair of small front rolls 33 and a corresponding pair of rear rolls, these two sets of rolls supporting a larger press roll 34 which is held continuously against the peripheral surface of the yarn body on the beam during the winding operation. For this purpose the bracket 32 is mounted on an arm fixed to a square shaft 35 which projects beyond the right-hand end, Fig. 1, of the parts there shown; and a long lever arm is fixed to the outer end of said shaft and extends backwardly toward the creel. Normally it lies approximately horizontally and it carries an adjustable weight which operates through the connections just described to force the roll 34 upwardly.

An extension 36, Fig. 1, of the presser roll shaft 35 is connected with a trip shaft 37, coaxial with the shaft 35, and an arm 38, Fig. 3, fast on said shaft 36 and carrying a roll 40 at its outer end, 75

cooperates with a spring 41 to control the position of a latch or stop lever 42, pivoted at 43. During approximately the first half of the winding operation the foot 44 of an upright rack bar 5 rests on the upper end of the latch 42, as clearly shown in Fig. 3. A spring 46 encircles this rack bar and tends to force it downwardly and the rack teeth mesh with a pinion 49 fast on a shaft 47, Fig. 3, carrying the eccentric pivot pin 24.

Referring again to Fig. 3, it will be seen that as the winding operation progresses and the diameter of the yarn body on the beam 2 increases, the roll 40 will be forced downwardly, thus gradually pushing the upper end of the latch 42 outwardly, or toward the right, until it finally releases the foot 44. At this point the spring 46 forces the rack bar 45 down, thus revolving the shaft 47 through an angle of approximately 180° in a counterclockwise direction, Fig. 1, and thereby causing the eccentric pin 24 to carry the head 23 bodily to the left. This moves the arm or prong 27 of the head 23 out of contact with the friction lever 20, and brings the other arm 27' of said head into engagement with the right-hand side of said lever. Such action shifts the pressure of the lever 20 from the collar 28 to the collar 28' of the second friction mechanism, and thereby transfers the drive from the mechanism which has been performing this function to the other mechanism which, as above pointed out, is driven at a slower speed. The latter thereupon takes over the function of driving the loom beam and continues to do so until the winding operation has been completed.

At this time the full beam is removed from the machine and is replaced with an empty one. When the yarn ends have been secured to the latter and the winding operation is started again, the presser roll 34 is eased up to meet the beam, thus causing the arm 38, Fig. 3, and the roll 40 to raise the rack bar 44 to its initial position, as shown in said figure, where it is again caught and held by the latch 42. Simultaneously with this action the eccentric pin 24 is swung back in a clockwise direction into its initial position, as shown in Fig. 1, thus moving the arm 27' out of contact with the friction lever 20 and bringing the other arm 27 back against the left-hand side of that lever, as illustrated in Fig. 1. This restores the parts to their initial relationship, with the drive for the beam on the higher speed mechanism. The cycle of operations above described is then repeated.

It will be evident from the foregoing that this invention overcomes the difficulties experienced with the prior art drive since it divides the driving operation between the two mechanisms, one operating at a speed suited to the requirements of the building of approximately the first half of the yarn body and then automatically shifting the drive to the other mechanism which operates at a lower speed suited to the requirements of completing the winding operation. Thus the friction created in each mechanism is moderate, the wear on the friction surfaces is reduced to satisfactory values, and the shift from one to the other takes place entirely automatically without any attention on the part of the machine operator.

While I have herein shown and described a preferred embodiment of my invention, it will be evident that the invention may be embodied in other forms without departing from the spirit or scope thereof.

Having thus described my invention, what I desire to claim as new is:

1. In a slasher having means for supporting a loom beam for the winding thereon of the sized yarn, driving means for said beam comprising two friction mechanisms both operatively associated with said beam to revolve it, said mechanisms being so organized as to operate by variations in the degree of frictional slip to drive said beam throughout different speed ranges, one higher than the other, and mechanism for automatically shifting the drive from one of said mechanisms to the other at an intermediate point in the building of the yarn body on said beam.

2. In a slasher having means for supporting a loom beam for the winding thereon of the sized yarn, driving means for said beam comprising two friction mechanisms both operatively associated with said beam to revolve it, said mechanism being so organized as to operate by variations in the degree of frictional slip to drive said beam throughout different ranges of speed, one substantially higher than the other, and means for shifting the drive from the higher to the lower speed mechanism automatically in response to an increase of predetermined magnitude in the diameter of the yarn body on the beam.

3. In a slasher having means for supporting a loom beam for the winding thereon of the sized yarn, driving means for said beam comprising two friction mechanisms both operatively associated with said beam to revolve it, said mechanisms being so organized as to operate by variations in the degree of frictional slip to drive said beam throughout different ranges of speed, one substantially higher than the other, and mechanism for automatically shifting the drive from the higher to the lower speed mechanism when the yarn body on said beam has attained substantially a predetermined size.

4. In a slasher having means for supporting a loom beam for the winding thereon of the sized yarn, driving means for said beam comprising two friction mechanisms both operatively associated with said beam to revolve it, one at a substantially higher speed than the other, a presser roll mechanism acting on the yarn body on said beam during the winding operation to compress and compact the yarn, and means controlled by the position of the presser roll as the winding operation progresses for shifting the drive automatically from the higher to the lower speed mechanism when said yarn body has attained substantially a predetermined size.

5. In a slasher having means for supporting a loom beam for the winding thereon of the sized yarn, driving means for said beam comprising two friction mechanisms both operatively associated with said beam to revolve it, said mechanisms being so organized as to operate by variations in the degree of frictional slip to drive said beam throughout different speed ranges, one higher than the other, a control member cooperating with said mechanisms to throw either into operation, as desired, and simultaneously to throw the other out of operation, and mecha-

nism for automatically moving said control member to shift said drive from the high speed to the low speed mechanisms at an intermediate point in the building of the yarn body on said beam.

5 6. In a slasher having means for supporting a loom beam for the winding thereon of the sized yarn, driving means for said beam comprising two friction mechanisms both operatively associated with said beam to revolve it throughout different speed ranges, one higher than the other, a control member cooperating with said mechanisms to throw either into operation, as desired, and simultaneously to throw the other out of operation, spring biased means for moving said control member to shift the drive from one of said mechanisms to the other, a latch restraining said spring biased means, and mechanism for automatically releasing said latch when the yarn body on said beam has attained substantially a predetermined size and thereby shifting said drive from one of said mechanisms to the other.

10 7. In a slasher having means for supporting a loom beam for the winding thereon of the sized yarn, driving means for said beam comprising two friction mechanisms both operatively associated with said beam to revolve it, one at a higher speed than the other, a lever operable to shift said drive from one of said mechanisms to the other, weighting means acting on said lever to produce the friction utilized in each of said mechanisms in driving the beam at either a high or low speed, and means responsive to changes in the diameter of the yarn body on said beam as the winding operation progresses to shift said lever from one position to another and thereby to change the drive from the higher speed to the lower speed.

15 8. In a slasher having means for supporting a loom beam for the winding thereon of the sized yarn, driving means for said beam comprising two friction mechanisms both operatively associated with said beam to revolve it throughout different speed ranges, one higher than the other, a lever mounted between said mechanisms for applying pressure to either of them, as desired, and thereby selectively bringing either into operation to drive said beam, a weighting mechanism acting on said lever to apply pressure to either mechanism, and means operable automatically in response to an increase of predetermined magnitude in the diameter of the yarn body on said beam to shift the action of said weighting mechanism from one side of said lever to the other and thereby to shift the drive of said beam from one of said mechanisms to the other.

20 9. In a slasher having driving means for the loom beam as defined in preceding claim 8 and including a press roll for acting on the yarn body on said beam as the winding operation progresses to consolidate said body, a construction in which said shift of said weighting mechanism from one side of said lever to the other is initiated by connections controlled by the position of said press roll.

ARTHUR E. SILCOX.
